ALONZO LINTON BAUSMAN, OF CHICOPEE, MASSACHUSETTS, ASSIGNOR TO NATIONAL EQUIPMENT COMPANY, OF SPRINGFIELD, MASSACHUSETTS, A CORPORATION OF MASSACHUSETTS.

BRUSH-LINED SIEVE.

1,141,863.

Specification of Letters Patent. Patented June 1, 1915.

Application filed May 10, 1913. Serial No. 766,915.

To all whom it may concern:

Be it known that I, ALONZO LINTON BAUSMAN, a citizen of the United States of America, residing at Chicopee, in the county of Hampden and State of Massachusetts, have invented new and useful Improvements in Brush-Lined Sieves, of which the following is a specification.

This invention relates to a brush-lined 10 sieve construction of improved form. Devices of this kind are used in cleaning apparatus for candy. An apparatus of this nature is fully disclosed in patent to Carlson, No. 527,662, issued October 16, 1894. 15 The improvement herein described relates chiefly to the construction of the brush-lined sieve, and since the apparatus generally in which it is used is disclosed in the patent referred to, the description will be herein 20 limited to the special form of sieve showing the invention. The brush-lined sieve shown in the patent to Carlson above referred to is constructed of a continuous sieve-portion through the holes of which 25 the brush bristles extend. The disadvantage in this construction is the difficulty of building the sieve with the bristles properly distributed over its surface. Furthermore, the bristles are frequently injured when 30 passed through the holes in the sieve.

The object of this invention is to build a brush-lined sieve with the bristles properly distributed over the surface thereof in functional coöperation with the sieve openings, 35 but not passing therethrough.

A further object is to construct such a sieve that any worn or injured parts can be replaced in a convenient manner.

A still further object is to provide a sieve 40 which is easier to build than the ordinary brush-lined sieve and a sieve which, when built, is more conveniently and efficiently arranged than former structures.

With these objects in view, the invention 45 is herein described in connection with the accompanying drawings, for the purpose of illustrating one preferred form of the invention.

In the drawings,—Figure 1 is a cross-section through one of the cross-supporting ribs of the sieve. Fig. 2 is a sectional view, taken on line 2—2 of Fig. 1. Fig. 3 is a perspective view of one of the sieve-strips used in building up the invention.

50 In the form shown, the sieve is generally

made up of parallel, longitudinal supporting-members joined together by cross-ribs, such as *a*, shown in the drawings. A description of one section of the sieve will make the construction clear.

60

A series of brush-holding strips *d* are spaced in parallel relation to join the cross-members *a* together. It is found convenient to provide recessed divisions in the members *a*, in which strips *d* rest. In order to hold 65 these brush-holding strips within the recesses, a series of sieve-forming strips *b* are shaped up, as shown in Fig. 3, having openings *e* therein and provided with down-turned ends adapted to rest on the edges of 70 brush-holding strips *d*. Where the strips *b* cross the ribs *a*, screws *c* are passed through the adjacent openings *e* to bind these strips to the cross-ribs. The screws *c* act through 75 the overlapping edges of the two series of strips to firmly hold all the strips on the cross-ribs. Between each two brush-forming strips *b* a sieve-forming strip is placed so that the two kinds of strips alternate. In 80 this way, the brushes have openings on each side so that in cleaning the articles in the sieve the material separated from the article falls readily through the sieve. Whenever a 85 brush or sieve portion is injured or worn, that portion can be readily replaced without disturbing the other portions which are still in efficient condition.

Applicant has shown one preferred form 90 of his invention for purposes of illustration only and not for the purpose of limiting the broad invention to the specific form shown.

What I claim is,—

1. A brush-lined sieve, comprising brush-holding members together with separate 95 sieve-forming strips, said members being constructed with the bristles adjacent to but not passing through the openings of the sieve.

2. A brush-lined sieve, comprising brush-holding members and separate sieve-forming strips, together arranged with the bristles of said members extending above and adjacent to the said means but without passing 100 therethrough.

3. A brush-lined sieve, comprising a series 105 of sieve-forming strips, a series of brush-forming strips to coöperate therewith, supporting means for both series of strips, all constructed and arranged so that each of 110

said brush forming strips can be replaced independently of the others, all for the purpose described.

4. A brush-lined sieve, comprising supporting means having removably-mounted thereon a series of brush-forming strips, a series of separate sieve-forming strips, several of each series of strips being arranged in alternating arrangement with each other on said supporting means, all for the purpose described.

5. A brush-lined sieve, comprising supporting means having a series of separate parallel brush-forming strips arranged in spaced relation on the supporting means, a series of parallel sieve-forming strips arranged in the spaces between the first-men-

tioned series of strips, all for the purpose described.

6. A brush-lined sieve, comprising supporting means having a series of parallel brush-forming strips arranged in spaced relation on the supporting means, a series of parallel sieve-forming strips arranged in the spaces between the first-mentioned series of strips, the edges of each series of strips lying in overlapping relation to the edges of the other series, and means to fasten the top overlapping set of strips directly to the supporting means, all for the purpose described.

ALONZO LINTON BAUSMAN.
